(57) **CLAIM**

The ornamental design for a flower covering, as shown and described.

DESCRIPTION

FIG. 1 is a front view of a first embodiment of a flower covering showing my new design in a flattened state and having a transparent surface;

FIG. 2 is a side view thereof in a flattened state;

FIG. 3 is a top view thereof in an expanded state;

FIG. 4 is a side view of FIG. 3;

FIG. 5 is front view of FIG. 3;

FIG. 6 is a perspective view thereof in a flattened state; and, FIG. 7 is a side view similar to that of FIG. 2 of a second embodiment of a flower covering showing my new design, in a flattened state and having an opaque surface.
